United States Patent

Des. 237,620
Patented Nov. 11, 1975

237,620

REFRIGERATOR DEODORANT CONTAINER

David A. Jones, Bellbrook, and Howard H. McIlvain,
Cincinnati, Ohio, assignors to The Drackett Company,
Cincinnati, Ohio

Filed Oct. 21, 1974, Ser. No. 516,067

Term of patent 14 years

Int. Cl. D23—04

U.S. Cl. D23—150

FIG. 1 is a top perspective view of a refrigerator deodorant container showing my new design;

FIG. 2 is a bottom perspective view thereof;

FIG. 3 is a top plan view thereof;

FIG. 4 is a side elevational view thereof taken from the front of FIG. 1;

FIG. 5 is a bottom plan view thereof.

We claim:

The ornamental design for a refrigerator deodorant container, as shown and described.
